DRESS SHIELD

Grace L. Fowler, Oklahoma City, Okla.

Application October 28, 1942, Serial No. 463,675

3 Claims. (Cl. 2—53)

This invention relates to dress shields.

An object of this invention is to provide an improved dress shield which includes a holder and a pad, the pad being removably secured to the holder.

Another object of this invention is to provide in a device of this kind a flexible holder provided with clamping tabs for clamping the pad on the outer side of the holder, the tabs and holder having complementary snap fastener elements for securing the tabs in clamping position.

A further object of this invention is to provide a device of this kind wherein the holder is made out of flexible plastic or similar moisture-proof material, and the holder is provided with means to permit securing it to a garment without puncturing the holder.

A further object of this invention is to provide a device of this kind in which the removable moisture absorbing part thereof is so held to the holder as to prevent curling or rolling of the edges of the cloth.

A further object of this invention is to provide in a device of this kind an improved clamping means for the cloth pad which is so constructed as to permit movement of the pad relative to the holder so as to thereby relieve any strain on the holder or the garment to which the holder is attached.

The invention consists of the novel construction, combination and arrangement of parts as will be more specifically referred to and illustrated in the accompanying drawing wherein is shown an embodiment of the invention, but it is to be understood that changes, variations and modifications may be resorted to which fall within the scope of the invention as claimed.

In the drawing:

Figure 1 is a detail side elevation partly broken away and in section of a dress shield constructed according to an embodiment of this invention.

Figure 2 is a sectional view taken on the line 2—2 of Figure 1.

Figure 3 is an enlarged fragmentary sectional view of a portion of the device, and

Figure 4 is a fragmentary sectional view taken on the line 4—4 of Figure 1.

Referring to the drawing, the numeral 10 designates generally a moisture-proof holder, and the numeral 11 designates generally a moisture absorbing pad which is mounted over the holder 10.

The holder 10 includes an inner crescent-shaped body 12, an outer crescent-shaped body 13 which is of a size slightly smaller than the

size of the inner body 12. The two bodies 12 and 13 are secured or connected together along their concave edges by means of a connecting strip 14 which has the opposite longitudinal edges thereof folded inwardly as at 15, and the strip 14 is then secured by stitching 16 to the concave edge of the body 12 and by stitching 17 is secured along the concave edge of the body 13. The convex edge of the body 12 has secured thereto a binding strip 18 which is U-shape in transverse section and is secured about the convex marginal edges of the body 12 by stitching 19. The body 13 also has secured about the convex marginal edges thereof a U-shaped binding 20 which is secured as by stitching 21.

The pad 11 comprises an inner crescent-shaped moisture absorbing body 22 and an outer crescent-shaped moisture absorbing body 23. The two bodies 22 and 23 are secured together along their concave edges by means of stitching 24. The pad 11 when in applied position is disposed as shown in Figure 2 over both of the bodies 12 and 13 and has the convex edge thereof projected slightly beyond the convex edges of the holder 10 as shown more clearly in Figure 4.

In order to provide a means whereby the pad 11 may be removably secured on the holder 10 in such a manner as to permit slight movement of the pad 11 with respect to the holder 10, I have provided a pair of clamping straps 25 which are secured in spaced apart relation to the body 12 on the inner side thereof and I have also provided a second pair of straps 26 which are secured to the holder 13 on the outer side thereof. The strap 25 extends inwardly from the marginal edge of the body 12 being secured at its outer end beneath the binding 18 and the inner or free end of the strap 25 has secured thereto one part 27 of a snap fastening means.

A complementary snap fastening part 28 is secured to the body 12 inwardly from the marginal edge thereof and the pad 11 is formed with an opening or slot 29 inwardly from its outer convex marginal edge through which the strap 25 is adapted to be extended. When the strap 25 is in a clamping position, the strap will be as shown in Figure 2 with the body 22 of the pad 11 covering the two snap fastener elements 27 and 28. In other words, the opening 29 in the body 22 is positioned outwardly from the snap fastener elements so that these elements will not come into contact with any portion of the body or the garment with which the shield is being worn.

The strap 26 is adapted to be extended through an opening 30 formed in the body 23 inwardly

from the marginal edge thereof and the inner free end of the strap 26 has one part 31 of a snap fastener element secured thereto. A complementary part 32 of the snap fastener element is secured to the body 13 of the holder 10 in such a position that when the snap fastener elements 31 and 32 are in fastening position, these elements will be covered by the body 23 at a point inwardly from the opening 30. There are two straps 25 and also two straps 26 which are positioned as shown in Figure 1.

A pair of clamping straps 33 and 34 are secured to the upper side of the connecting strip 14 adjacent the opposite ends thereof. The two straps 33 and 34 are of like construction and each strap is provided with a reverted outer end portion 35 which is secured to the connecting strip 14 by the stitching 16 and 17. The straps 33 and 34 are extended through the openings 36 which are formed in the pad 11 along the connecting concave edges thereof and the free ends of the straps 33 and 34 have secured thereto one part 37 of a snap fastener element. A complementary part 38 of the snap fastener element is secured to the connecting strip 14 inwardly from the opening 36 so that the two snap fastener parts 37 and 38 will underlie the pad 11 inwardly from the openings 36.

The shield is adapted to be firmly secured on the garment of the wearer by means of safety pins or the like, and in order to provide means whereby the shield will not be torn, I have provided grommets 39 and 40 which are secured to the body members 12 and 13 adjacent the convex edges thereof and substantially midway between the junction between the concave and convex edges of these bodies. I have also provided a second pair of grommets 41 and 42 which are secured to the connecting strip 14 adjacent the opposite ends thereof. The grommets 41 and 42 are extended through the folded or reverted portions of the straps 33 and 34, as shown more clearly in Figure 3, and provide an additional securing means for the upper clamping straps 33 and 34.

The grommets 39 and 40 are adapted to be covered by the outer or lower portions of the pad members 22 and 23, as shown more clearly in Figure 4 so that the metal forming the grommets 39 and 40 will not come into direct contact with the body or arm or any portion of the garment.

In the use of this shield, the pad 11 may be initially clamped or attached to the holder 10 by threading the clamping straps 25 and 26 through the openings 29 and 30, respectively, and also threading the straps 33 and 34 through the openings 36 in the pad 11. The shield may then be secured within the garment in the usual position, that is, in the armpit of the garment, safety pins or other fastening means being extended through the grommets 39, 40, 41 and 42. While the shield is being worn, the pad 11 may have relative movement with respect to the holder 10 by reason of the engagement of the securing straps through the openings in the pad. These openings provide a slipping connection between the pad and the holder so that a slight movement may be had between these two members. The holder 10 is preferably constructed out of moisture-proof material, such as a flexible plastic or the like, whereas the pad 11 is constructed out of moisture absorbing material which can be cleaned upon the removal from the holder 10.

What I claim is:

1. A dress shield comprising a flexible holder formed of a pair of crescent-shaped members, an elongated connecting strip, stitching securing the opposite longitudinal edges of said strip to the concave edges of said pair of members, a pad member folded over said holder, said pad member including a pair of crescent-shaped moisture absorbing bodies, stitching securing the concave edges of said bodies together, said bodies having spaced openings therethrough adjacent the marginal edges thereof, a plurality of inwardly extending pad securing straps carried by said holder and extendible through said openings, and complementary fastener elements carried by the inner ends of said straps and said holder for removably securing said pad on said holder.
2. A dress shield comprising a flexible holder formed of a pair of crescent-shaped members, an elongated connecting strip, stitching securing the opposite longitudinal edges of said strip to the concave edges of said pair of members, a pad member folded over said holder, said pad member including a pair of crescent-shaped moisture absorbing bodies, stitching securing the concave edges of said bodies together, said bodies having spaced openings therethrough adjacent the marginal edges thereof, a plurality of inwardly extending pad securing straps carried by said holder and extendible through said openings, complementary fastener elements carried by the inner ends of said straps and said holder for removably securing said pad on said holder, and a plurality of grommets carried by said holder adjacent the marginal edges thereof.
3. A moistureproof holder, a moisture absorbing pad mounted over the holder, said holder including an inner crescent-shaped body, an outer crescent-shaped body of a size slightly smaller than the size of the inner body, the said two bodies being secured together along their concave edges by means of a connecting strip which has the opposite longitudinal edges thereof folded inwardly and said strip then being secured by stitching to the concave edges of the bodies, a U-shaped binding strip secured to the convex edges of the bodies by stitching, said absorbing pad when in applied position being disposed over both of said crescent-shaped bodies and having the convex edge thereof projected slightly beyond the convex edge of the holder, a pair of clamping straps secured in spaced apart relation to the inner body on the inner side thereof, a second pair of straps secured to the outer body on the outer side thereof, said straps extending inwardly from the longitudinal edges of the bodies, being secured at their outer edges beneath the binding, and the inner free ends of the straps each having secured thereto one part of a snap fastener means, complementary snap fastening parts secured to the body inwardly from the longitudinal edge thereof, and said pad being formed with openings or slots inwardly from its outer convex longitudinal edges through which said traps are adapted to be extended, said snap fastener elements being so positioned that they will not come into contact with the body of the wearer, grommets extended through said U-shaped bindings and adapted to be covered by the outer lower portions of the pad members.

GRACE L. FOWLER.
